SOUND RECORDING APPARATUS

Arthur E. Reeves, Los Angeles, Calif.

Application September 14, 1942, Serial No. 458,236

12 Claims. (CL. 179—100.3)

This invention relates to sound recording apparatus, and more particularly to apparatus that utilizes a glow tube.

This application is a continuation in part of an application filed January 16, 1939, in the name of Arthur E. Reeves, under Serial Number 251,155, and entitled "Glow tube," and patented on November 3, 1942, No. 2,300,809.

Glow tubes of the character illustrated in said prior application are also described and claimed in Patent No. 2,270,967, granted January 27, 1942, to Arthur E. Reeves, for a glow tube.

Such glow tubes in general include spaced electrodes between which a glow or actinic radiations are produced, the intensity of which is varied in accordance with the impulses to be recorded. This varying illumination is caused to affect a sensitized film that is moved past the glow. In this way, a variable density sound track is produced.

In the forms of glow tubes described in said prior application and prior patent, the electrodes between which the glow is produced are flat, closely spaced plates, and the space between the plates is presented edgewise to the sensitized surface. By appropriate insulation supports, the glow is confined between the opposed electrode surfaces.

It has been proposed in the past to produce two cooperating push-pull sound tracks for recording the impulses. Such sound tracks are characterized by the fact that one is the complement of the other; therefore as the density of one component track varies longitudinally of the two tracks, the density of the other component varies in the opposite direction. The advantages of such a push-pull arrangement are now well-understood, both for recording and reproduction.

The electrical impulses that are to be recorded are almost invariably amplified before they serve to modulate the intensity of illumination or glow produced by the glow tube. Accordingly when a push-pull type of track is to be recorded, it is necessary to use amplifier stages likewise arranged in push-pull relation. For optimum results, the amplifier stages must be balanced, and the glow tubes that produce the varying light intensities must also have identical characteristics. These ideal conditions are difficult to approximate in systems operating in accordance with the prior art.

It is one of the objects of this invention to make it possible easily to balance the glow tube effects, and thereby to approach the ideal conditions for accurate push-pull recording.

This object is accomplished by providing a unitary glow tube structure that is capable of producing both complementary glows. Thus for example, the glow tube may have a common anode, large enough simultaneously to cooperate with a pair of cathodes. The glow between the anode and each of the cathodes affects separate portions of the sensitized photographic film. The balancing of the two tracks involves careful consideration to the dimensional accuracy of the electrodes and their spacing. By placing both cathodes in the same envelope, both glows exist under identical fluid pressure conditions.

In the event separate glow tubes were utilized to obtain the glows for recording the complementary tracks, these tubes would have to be chosen by trial and error, until a pair be found having closely matching characteristics. Since most tubes are filled with a mixture of inert gases at low pressures, any variation for example in the mixture contributes in no small measure to the difficulties encountered in the process of matching up the tubes. And in addition, dimensional variations also complicate this matching up process.

It is accordingly another object of this invention to provide a unitary glow tube structure for push-pull recording, in which the glow effects are produced in a common envelope.

30 In the prior application hereinabove identified, a lens system is described and claimed for determining the final dimensions of the image of the glow that is focused upon the sensitized photographic surface. In this way, the full glow can be utilized, and the necessity of using mechanical slits is obviated. It is another object of this invention to adapt the push-pull tube structure for cooperation with a lens system of this character.

This invention possesses many other advantages, and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of this invention is best defined by the appended claims.

Referring to the drawings:

Figure 1 is a view, mainly in longitudinal section, illustrating an apparatus incorporating the invention;

Fig. 2 is a sectional view taken along the plane 2-2 of Fig. 1;

Fig. 3 is an end view of the lens barrel utilized in connection with the invention, and viewed from plane 3-3 of Fig. 1;

Fig. 4 is an end view of the lens barrel taken from the right of Fig. 1;

Fig. 5 is a fragmentary sectional view, taken along plane 5-5 of Fig. 1;

Fig. 6 is a sectional view, taken along plane 6-6 of Fig. 5;

Fig. 7 is a fragmentary plan of a push-pull sound track produced by the aid of the invention; and

Fig. 8 is a wiring diagram of an electric recording system incorporating the invention.

The glow tube structure includes a sealed transparent envelope or container 1 (Figs. 1 and 2), having a rounded end. In the present instance this envelope is shown as telescoped within a tubular mounting 2. In one end of mounting 2 there is an aperture 3 through which the light radiations produced within the tube are passed to a lens system provided in a lens barrel 4. The manner in which the lens barrel is supported will be hereinafter described. It is sufficient for the moment to point out that the lens system serves to focus the images of the glow discharge upon a suitable sensitized surface.

The envelope 1 may be held within the mount 2 in any suitable manner; for example, the base 5 of the glow tube may carry a split ring 6. This ring is tightly clamped as by the aid of the screw 7 upon the base 5. Rods 8 are carried by the enlarged flange 9 of the mount 2. They pass through appropriate apertures 10 in the ring 6. A thumb screw 11 is threaded into the ring 6, and has a flange 12 which clamps against one of the rods 8.

The lens barrel 4 is shown as having a flange 13. This flange 13 is guided for axial movement by the aid of the guide pin 14 fastened in the mount 2. This pin 14 is engaged in a guiding aperture 15 formed in the flange 13. The barrel 4 is urged resiliently toward the right, as by the aid of a compression spring 16 disposed between the end wall of the mount 2 and the flange 13.

The lens system may be adjusted axially for the purpose of focusing by the aid of a focusing sleeve 17. This focusing sleeve has a running fit with respect to the barrel 4 and engages the right hand surface of flange 13. It is also provided with an externally threaded extension 18 adapted to be in threaded engagement with the tubular extension 19 formed on the mount 2. The inner cylindrical surface of extension 18 has a running fit with the flange 13. Accordingly if it is desired to move the barrel 4 toward the left as viewed in Fig. 1, the sleeve 17 is manipulated so as to turn the extension 18 inwardly with respect to the extension 19, thereby further compressing the spring 16. If it be desired to move the lens barrel 4 toward the right, the focusing sleeve 17 is turned in a direction to disengage the threads of the extension 18 from threads of the extension 19, thereby permitting the spring 16 to expand and to urge the flange 13 against the end wall of focusing sleeve 17.

As explained in the prior patent hereinabove referred to, electrodes are supported within the envelope 1, which, when supplied with suitable electrical potentials, form a glow that may be modulated in accordance with the sound impulses to be recorded. These electrodes are shown most clearly in Figs. 5 and 6. Thus there is an elec-

trode structure 20 formed of sheet metal, and supported in a massive block of insulation 21. This block of insulation 21 is shown as appropriately grooved so that the upper surface 22 of the block 21 is coincident with the upper surface of the electrode structure 20. The block 21 may be made of lavite.

Juxtaposed to the active upper surface of the electrode 20 are the two electrodes 23 and 24. These two electrodes are also made of appropriate sheet metal and are supported by an insulation block 25, similar to block 21. The active surfaces of electrodes 23 and 24 are portions of a continuous plane, and are placed closely adjacent to each other. These electrode surfaces cooperate with different portions of the electrode 20, which has an active upper surface coextensive with the combined active surfaces of electrodes 23 and 24.

In order to hold the electrode structure in proper assembled relation, each of the blocks 21 and 25 is provided with a side flange 26 or 27 respectively. These flanges as shown most clearly in Fig. 5, contact the adjacent surface of the opposite block 21 or 25, to form a rectangular narrow opening or space 28 between the electrodes. Furthermore, in order to ensure against sputtered metal (that may be deposited upon the insulation blocks 21 and 25) from bridging the electrodes, the space 28 between the electrodes is kept open as much as possible on all sides. For this reason the side flanges 26 and 27 are slotted as indicated by the slot 29 in Fig. 1. All this is shown and described in the said prior patent hereinbefore referred to.

The insulation blocks 21 and 25 with the electrodes 20, 23 and 24 are held in assembled relation by the aid of the bolts 30 which pass through the side portions of the insulation blocks 21 and 25.

The electrical connections for the electrodes 20, 23 and 24 are provided by conductors 31, 32 and 33. These conductors are made quite large in diameter, to serve as well as supports which pass through the press 34 of the evacuated container 1. These conductors terminate in prongs such as 35, 36, supported at the end of the base 5, and adapted to cooperate in a well-known manner with a suitable receptacle.

In order to lend further rigidity to the support of the electrode structure upon the press 34, an additional metallic support 37 (Fig. 2) similar to the conductors 31, 32 and 33 is joined to the common electrode 20 and is imbedded in the press 34.

The circuit arrangements are such that two glow discharges are formed: one between the electrode 20 and electrode 23; and another between electrode 20 and electrode 24. The space discharges between these electrodes are so modulated that they are in push-pull relationship. For this purpose the electrode 20 for example, can be an anode, and electrodes 23 and 24 can be cathodes. They are so indicated in the diagram of Fig. 8. In this diagram, electrode 20 is shown as connected to the positive terminal of a source of direct current energy, such as the battery 38. The negative terminal of the battery is connected to the central tap of the secondary coil 39 of the transformer 40. The terminals of the secondary coil 39 are connected respectively to the cathodes 23 and 24.

The primary coil 41 is connected to the output of amplifier system 42. This amplifier system serves to amplify sound impulses fed to the

input of the system 42 as by the aid of a microphone 43.

Assuming that there are no signaling impulses flowing in the circuit associated with the microphone 43, a glow of intermediate intensity is caused to be produced between each of the electrodes 23, 24 and the anode 20. Such an intermediate glow may be determined by proper choice of battery potential, which is made effective across the electrodes.

When a signaling impulse is transmitted, an electromotive force is induced in the secondary coil 39. If we assume that the impulse is in such direction as to make the upper terminal of coil 39 positive, then the potential of electrode 24 is made more positive than before, and the potential of the other electrode 23 is made less positive. The glow between cathode 24 and anode 20 is accordingly reduced, because the potential difference between these two electrodes is reduced. At the same time, the glow between electrode 23 and anode 20 is increased. Upon a change in sign of the impulses, the glow increases between cathode 23 and anode 20. Since the impulses to be recorded are passed to the glow tube circuit through a transformer such as 40, the potentials across the coil 39 change in sign in accordance with the impulses in the microphone circuit.

The production of a glow discharge between the electrodes by appropriate choice of potential differences is readily obtained, especially when the pressure and character of the gaseous filling in the envelope 1 are suitably chosen. The gaseous filling in the envelope 1 is usually a mixture of inert gases, such as a mixture of several of the noble monatomic gases.

The two discharges, respectively between anode 20 and cathode 24 and between the anode 20 and cathode 23, are presented edgewise to the lens system in lens barrel 4. This lens barrel 4 is so arranged that the images of these two space discharges are focused upon a photographic film that passes at uniform speed transversely past the right hand end of the barrel 4. As explained in the prior application hereinabove referred to, the lens system in the barrel 4 can comprise cylindrical lenses that determine the width as well as the thickness of the glow images.

Thus for example, as shown most clearly in Fig. 3, a pair of cylindrical lenses 46 and 47 is illustrated as being disposed respectively to receive the illumination of the glow discharges formed between electrodes 20 and 23, and between electrodes 20 and 24. These cylindrical lenses 46 and 47 have vertical axes. Accordingly they serve to reduce the width of the glow image, in a horizontal direction. As shown most clearly in Fig. 3, these lenses are set closely together, to correspond to the spacing of the electrodes 23, 24. Accordingly it may be necessary to cut away the adjacent edges of these lenses; but this has no appreciable effect upon the optical properties of the lenses.

Similar cylindrical lenses 48 (Fig. 4) are disposed with horizontal axes, within the barrel 4, to reduce the thickness or vertical dimension of the image of the glow. These lenses are exposed at the right hand end of the barrel 4. The ultimate dimensions of the glow images are made to conform to suitable values, without masking out any of the glow. Intensely luminous images can thus be produced, and there is a corresponding improvement in the faithfulness of the record.

The photographic film or phonofilm 49 (Fig.

7) upon which the sound tracks 44 and 45 are to be photographed, is fed past the lens system at a uniform rate. Tracks 44 and 45 are of such a nature that a dark portion along one track is opposite a light portion on the other track, thus conforming to the push-pull pattern.

In view of the fact that both of the glow discharges occur in a common evacuated envelope 1 (which encloses all of the electrodes and their supports), it is a simple matter to balance the glow discharges so that they substantially accurately correspond to the ideal push-pull requirements.

Furthermore, in order to ensure that the illumination of one glow discharge will not interfere with that of the other, separating shields in the form of septa are provided. For example, a semi-circular shield or septum 50 (Figs. 1, 2 and 5) may be supported upon insulation blocks 21 and 25, and having its main plane disposed between the two glows. This plate 50 may be made of refractory material such as thin mica. It may be provided with a slot 51 to permit it to be passed over the outer surfaces of the blocks 21 and 25. It may be held in place upon the blocks by the aid of the bolts 55 that pass through oppositely directed projections 52 and 53. These projections are formed integrally with the blocks 21 and 25.

A corresponding septum 54 is carried by the lens barrel 4 and is disposed between the two lenses 46 and 47. This septum may be of thin metal, such as copper, anchored in the anchor pins 56. These anchor pins 56 may be supported in the flange 13 of the lens barrel 4.

The septa 50 and 54 are arranged to cooperate with each other by virtue of the guiding rods 8 and the guide pin 14, in such manner that the main planes of these septa are coincident. Cross illumination from the path of one glow discharge to the path of the other is thus substantially entirely prevented by the septa.

What is claimed is:

1. In combination, a pair of substantially equal electrodes having discharge surfaces disposed side by side, said surfaces forming portions of a continuous surface, a common electrode structure having a discharge surface substantially coextensive with the said first discharge surfaces and spaced therefrom so as to cooperate therewith and to form a pair of space discharge paths, and a common sealed envelope for all of said electrodes.

2. In combination, a pair of substantially equal electrodes having discharge surfaces disposed side by side, said surfaces forming portions of a continuous surface, a common electrode structure having a discharge surface substantially coextensive with the said first discharge surfaces and spaced therefrom so as to cooperate therewith and to form a pair of space discharge paths, means for shielding the illumination of the glow discharges from each other, and a common sealed envelope for all said electrodes and said shielding means.

3. In combination, a pair of substantially equal electrodes having discharge surfaces disposed side by side, said surfaces forming portions of a continuous surface, a common electrode structure having a discharge surface substantially coextensive with the said first discharge surfaces and spaced therefrom so as to cooperate therewith and to form a pair of space discharge paths, a common sealed envelope for all of said electrodes, and a pair of lens systems to which the discharge spaces are presented in edgewise fashion.

4. In combination, a pair of substantially equal electrodes having discharge surfaces disposed side by side, said surfaces forming portions of a continuous surface, a common electrode structure having a discharge surface substantially coextensive with the said first discharge surfaces and spaced therefrom so as to cooperate therewith and to form a pair of space discharge paths, a common sealed envelope for all of said electrodes, each of said lens systems being arranged to provide an image of substantially the entire glow that is associated with the respective system, said image having dimensions suitable to be focused upon a sensitized photographic surface.

5. In combination, a pair of substantially equal electrodes having discharge surfaces disposed side by side, said surfaces forming portions of a continuous surface, a common electrode structure having a discharge surface substantially coextensive with the said first discharge surfaces and spaced therefrom so as to cooperate therewith and to form a pair of space discharge paths, a common sealed envelope for all of said electrodes, a pair of lens systems to which the discharge spaces are presented in edgewise fashion, and means for shielding the illumination of the glow discharges from each other.

6. In combination, a plurality of electrodes, a sealed container forming a common space for the electrodes, said electrodes forming pairs of opposed electrode surfaces, said pairs being substantially identical, to provide a pair of space discharge paths of substantially equal characteristics, a push-pull amplifier system having its output connected to said electrodes to produce complementary glows across said paths, and a photo-sensitive film disposed so as to be exposed to both of said complementary glows at spaced areas of the film.

7. In combination, a pair of substantially equal electrodes having discharge surfaces disposed side by side, said surfaces forming portions of a continuous surface, a common electrode structure having a discharge surface substantially coextensive with the said first discharge surfaces and spaced therefrom so as to cooperate therewith and to form a pair of space discharge paths, a common sealed envelope for all of said electrodes, and a push-pull amplifier system having its output connected to said electrodes to produce complementary glows across said paths.

8. In combination, a pair of substantially equal electrodes having discharge surfaces disposed side by side, said surfaces forming portions of a continuous surface, a common electrode structure having a discharge surface substantially coextensive with the said first discharge surfaces and spaced therefrom so as to cooperate therewith and to form a pair of space discharge paths, insulation supports for the electrodes and the electrode structure, said supports covering substantially all of the electrodes but the active electrode surfaces, and a common sealed envelope for all of said electrodes and said supports.

9. In combination, a pair of substantially equal electrodes having discharge surfaces disposed side by side, said surfaces forming portions of a continuous surface, a common electrode structure having a discharge surface substantially coextensive with the said first dis-

charge surfaces and spaced therefrom so as to cooperate therewith and to form a pair of space discharge paths, insulation supports for the electrodes and the electrode structure, said supports covering substantially all of the electrodes but the active electrode surfaces, and a septum carried by said supports for segregating the illumination from the space discharge paths from each other, and a common sealed envelope for all of said electrodes, said supports and said septum.

10. In combination, a pair of substantially equal electrodes having discharge surfaces disposed side by side, said surfaces forming portions of a continuous surface, a common electrode structure having a discharge surface substantially coextensive with the said first discharge surfaces and spaced therefrom so as to cooperate therewith and to form a pair of space discharge paths, a pair of insulation blocks for respectively supporting said common electrode structure and the pair of electrodes, each of said insulation blocks covering substantially all of the respective electrode areas but the active surfaces, and said blocks each having a projection extending away from the active surfaces, and a septum supported by the aid of said projections for segregating the illumination from the space discharge paths from each other.

11. In combination, a pair of substantially equal electrodes having discharge surfaces disposed side by side, said surfaces forming portions of a continuous surface, a common electrode structure having a discharge surface substantially coextensive with the said first discharge surfaces and spaced therefrom so as to cooperate therewith and to form a pair of space discharge paths, a pair of insulation blocks for respectively supporting said common electrode structure and the pair of electrodes, each of said insulation blocks covering substantially all of the respective electrode areas but the active surfaces, and said blocks each having a projection extending away from the active surfaces, and a septum supported by the aid of said projections for segregating the illumination from the space discharge paths from each other, each of said blocks having an integral spacer adjacent an edge thereof, and adapted to cooperate with the adjacent edge of the other block, to hold said blocks in spaced relation.

12. In apparatus for the production of a phonofilm having a glow discharge tube as the source of light and electrical means for modulating the glow in correspondence with sound variations; characterized in that the glow tube comprises a pair of sets of electrodes, each set having opposed closely spaced surfaces, sound modulated glows being produced in push-pull relations between the two sets of electrodes, the film being disposed in a plane such as to receive the edgewise glow of the tube, and a pair of lens systems, respectively interposed between the glows and the film and subtending respectively the entire sectional area of the glows and serving to focus substantially the total glows of the said edge upon the film and to condense the same to suitable dimensions for sound records thereby eliminating the use of slits and the like.

ARTHUR E. REEVES.
